Attorney

UNITED STATES PATENT OFFICE

WILLIAM A. MUELLER, OF WASHINGTON, DISTRICT OF COLUMBIA

SASH AND DOOR BOLT

Application filed August 10, 1927, Serial No. 211,938. Renewed April 18, 1929.

This invention relates to improvements in a door or window fastening device, and has for its object to provide a fastener which is applicable for use in connection with either 5 a window or door.

A principal object of the invention is to provide in a door or window fastener having a pivoted slide bolt a spring control therefor.

A further object of the invention is to provide, in combination with a window or door fastening device, filler or spacer bars for filling in space between the member being fastened and the fastener bolt.

With the above and such other objects in view as may hereinafter more fully appear, I have invented the device illustrated in the accompanying drawings, in which:

Figure 1 is a perspective view of my device in inoperative position;

20 Figure 2 is a similar view shown in operative position;

Figure 3 is a sectional elevational view of the device, shown attached to a window;

25 Figure 4 is a section of a door frame embodying my invention.

Figure 5 is a detail plan view of spacer bar;

Figure 6 are perspective views thereof.

Figure 7 is a perspective detail of the locking bolt.

30 Figure 8 is a perspective detail of a portion of the base member without the spring clip member.

Figure 9 is a plan view of the structure shown in Figure 3.

35 Like reference characters indicate like parts throughout the following specification and in the several views in the drawings in which 1 indicates a latch consisting of a U-shaped keeper 2, between the upper and lower walls 3 and 4 of which is mounted a bolt 5,

40 pivotally and slidably mounted between said walls 3 and 4 by means of a pin 6 operating in an elongated slot 7 in the member 5. This member 5 may be held in inoperative position parallel with the walls 3 and 4; by means of the pin 6, the said member 5 may be drawn to the rear extremity of the slot 7, and turned at right angles to said walls 3 and 4 and pushed through an opening 8 in the rear wall 9 of

45 the U-member to the forward limit of the

slot 7, whereby the member 5 will be held in rigid, fixed, right-angular position relative to the walls 4 and 5, and thus hold the door 10 fastened. To prevent the member 5 from slipping forward out of the opening 8, 55 through shaking or rattling of the door, in which case it would immediately drop to unlatched position, I provide a spring 11, held by the pin 6 having its rear end 12 formed into a roll to drop into the transverse groove 13 on the rear end 14 of the bolt 5; thus the bolt will be held by said spring against accidental displacement from its fastening position. The forward end of the member 5 is provided with opposing grooves 15 and 16, 60 which form finger holes by means of which the said lock member may be readily manipulated.

As it often happens that when a door is closed the plane of its outer surface 21 is inwardly of the plane of the frame 22, I provide a special spacer bar 24 of different transverse dimensions, the width of the surface 25 of which is substantially double the length of the width of the edge 26, and screw openings 70 27 are provided along the surface 25 and screw openings 28 are provided extending edgewise through the bar in order that the said block may be used in either position to space between the said door and the inner 75 surface of the bolt 5, when in operative position. I also provide another spacer bar 29, which may be seated upon the surface 26 in order to build up said surface, if the space between the door and bolt is not as great as the 80 width of the said bar 24.

In Figure 3 I show the device as a window latch, in which case the lower wall 4' is extended at each end to form ears 17 and 18, in which are provided screw holes 19, 90 whereby the device may be attached to the upper surface of the sash member 20; otherwise the construction is similar to the one previously described. These ears are essential elements in the construction as screws 95 cannot be placed through the walls 3' and 4' to hold the mounting member in place, because to do so would render the bolt 5' inoperative.

The spring 11' in this form of the inven- 100

tion is also an essential element, as without the spring to hold the lock against accidental or intentional movements through vibration by an unauthorized person, the bolt 5' might easily be caused to creep out of its locked position through constant tapping upon the outer surface of the window sash, after which a knife or other tool might be slipped between the sashes and the bolt thus 10 moved out of latching engagement with the lower sash. In the rear edge 30 of the wall 4 there is provided a recess 31 to receive the right angular flange 32 of the spring 11', whereby said spring is held against rotatable 15 action and secured in its proper position at all times.

Having now described my invention, that which I claim to be new, and desire to procure by Letters Patent, is:

20 1. A fastening device of the character described, comprising a U shaped base member having a rear wall, an aperture, a bolt pivoted to the base member and having slidable movement relative thereto and adapted to 25 project at end through said opening, and means fastened to the base member for holding the bolt bar against accidental movement, said means consisting of a leaf spring provided with roll end, a spacer bar forming a 30 seat for said bolt bar when in operative position, said space bar comprising a member of two different transverse dimensions and having a hole at each end of thickness.

35 2. A fastening device of the character described comprising a U shaped base member having a rear wall, an aperture, a bolt pivoted to the base member and having slidable movement relative thereto and adapted to project at end through said opening, and 40 means fastened to the base member for holding the bolt bar against accidental movement, said means consisting of a leaf spring provided with roll end, the under wall of base member having ear extending so that said 45 fastening device can be attached to window sash.

50 3. A fastening device comprising a U shaped base member, a bolt member carried thereby, and means for maintaining said bolt bar in operative position, said means consisting of a leaf spring provided with a roll end, and said bolt bar having a recess to receive said roll, and means for retaining said 55 leaf spring against lateral movement, said means including a right angular terminal on said leaf spring, and said bolt bar having grooves at end so that said bolt bar can be operated with ease.

60 4. A fastening device comprising a U shaped base member, a bolt member carried thereby, and means for maintaining said bolt bar in operative position, said means consisting of a leaf spring provided with a roll end and said bolt bar having a recess to 65 receive said roll, and means for retaining

said leaf spring against lateral movement, said means including a right angular terminal on said leaf spring, and a recess in said base member to receive said terminal.

5. In a device of the character described comprising an exposed bolt, a spacer member for said bolt when in operative position, said spacer member comprising a block of different dimensions having recesses extending transversely therethrough parallel to the 75 respective transverse dimensional axes, for purposes of adjustably securing said spacing member in several positions.

In testimony whereof I affix my signature.

WILLIAM A. MUELLER.
